UNITED STATES PATENT OFFICE.

JOHN E. ARTHUR, OF LANE, AND ROY L. ARTHUR, OF LE ROY, ILLINOIS; SAID ROY L. ARTHUR ASSIGNOR TO E. C. HERSCHEERGER, OF ARTHUR, ILLINOIS.

HOOF-CLIPPER.

1,145,459.

Specification of Letters Patent.

Patented July 6, 1915.

Application filed September 18, 1913. Serial No. 790,388.

To all whom it may concern:

Be it known that we, JOHN E. ARTHUR, a citizen of the United States, and a resident of Lane, in the county of DeWitt and State 5 of Illinois, and ROY L. ARTHUR, a citizen of the United States, and a resident of Le Roy, in the county of McLean and State of Illinois, have invented a new and useful Improvement in Hoof-Clippers, of which the 10 following is a specification.

Our invention relates to improvements in hoof clippers, and has for its principal object the provision of such a device which is simple in construction, easy to operate and 15 efficient in producing good results in the hands of an inexperienced workman.

A further object is the provision of a hoof clipper in which the knife coöperating jaw is first moved under the hoof of an animal, 20 and then the knife forced downwardly to clip the hoof.

Further objects include improvements in details of construction and operation.

To the accomplishment of the foregoing 25 and such other objects as may hereinafter appear, our invention consists in the construction, combination and arrangement of parts hereinafter described and then sought to be defined in the claims, reference being 30 had to the accompanying drawings forming a part hereof, and which show for illustrative purposes a preferred embodiment of our invention, it being understood however that various changes may be made within the 35 scope of the claims without digressing from our inventive idea.

In the drawings:—Figure 1 represents a side elevation of a device constructed according to our invention in position ready 40 to begin operation; Fig. 2 is a similar view of the operating parts at the completion of their operation; Fig. 3 is a view similar to Fig. 1, of the other side of such a device; Fig. 4 is a bottom plan view of the operating parts, and Fig. 5 is a perspective view of the rear end of the base member or handle.

Referring now to the drawings, the numeral 1 designates one of the handle members which forms or constitutes what might 50 be called a base member, having its end provided with the enlarged transverse member 2, having the sharpened lower edge 3 and depending extension 4 for the purpose of providing an anchorage or bearing for the

device when in operation, as will be explained later. This handle member is provided with a longitudinally extending slot 5, intermediate its ends, and has its other end bifurcated or forked, as at 6, to receive a portion of the other handle or operating member 7. Mounted so as to slide relative to said handle or base member 1, is the knife carrying member 8, having the spaced side members 9 extending along said handle or base member, which are connected by means of a pin 10, which is loosely slideable in slot 5. The head of this member 8 is provided with the knife member 11, as shown. The handle member 7 is pivotally connected to this member 8 by means of the pin 12 which passes through the boss or sleeve 13, on the end of said handle member 7. A pin 14 passes through the bifurcated or forked ends 6 of the handle or base member 1, pivotally connecting it to said handle member above the boss or sleeve 13. The handle member 7 is then bent to extend at an angle, as indicated at 15, and to this portion is pivotally connected, as by means of pin 16, member 17 which carries the jaw or blade to coöperate with the knife 11. This member 17 has its end bifurcated as at 18, to embrace the inclined portion 15 of the handle 7, and the pin 16 passes therethrough, forming a pivotal connection. The lower portion 19 of this member 17 is curved or substantially crescent shaped, as shown, and forms the jaw or anvil which coöperates with the knife 11. This lower portion 19 corresponds in width to the outside of said member 8, and the member 17 is accordingly reduced as at 20, so that it may have free movement between the spaced side members 9, of member 8. This member 17 has the slot 21 provided intermediate its ends, which slot is formed in two parts, 21' and 21'', at an obtuse angle to each other and the pin 22 mounted between the spaced side members 9 of member 8, moves in said slot. Secured to the pin 16 is the pruning knife member 23 which is pivoted intermediate its ends on pin 12, having the lower portion formed with the convex knife edge 24, which coöperates with a correspondingly curved concave portion 25, on the adjacent side member 9, of member 8. This provides the pruning knife or tree trimmer. Apertures 26 and 27 are provided in the handle members

1 and 7 for the purpose of attaching extensions to facilitate the operation of the device for either of its purposes.

In operation as a hoof clipper the device 5 is placed in the position shown in Fig. 1, with the foot of the operator on the rear portion of the base member 1. The handle member 7 is then moved downward, which 10 operation first causes the knife coöperating member 19 to move forwardly under the hoof of the animal, this movement being caused by the pivotal connection of member 17 with handle 7, and the pin 22 moving in the part 21" of slot 21. When the pin passes 15 the bend in the slot, the knife member 8 is caused to descend rapidly in a substantially vertical direction, and will clip the hoof of the animal.

The operation of the device as a pruning 20 knife or tree trimmer is obvious.

Among the advantages derived from this device may be included the leverage gained by the particular construction shown, which causes it to operate efficiently. Further, it 25 may be used either outdoors or indoors, that is on a floor or not. The arrangement for extending the handles adds to its utility.

What we claim is:—

1. In a device of the character described, 30 and in combination, a pair of handle members pivotally connected together, one of which forms a base member, a knife carrying member having a slideable and pivotal connection with one of said handle members 35 and a jaw or anvil member pivotally connected to the other of said handle members and adapted to coöperate with said knife carrying member having a slideable and pivotal connection therewith.

40 2. In a device of the character described and in combination, a pair of handle members pivotally connected together, one of which forms a base member, a knife carrying member having a slideable and pivotal connection with one of said handle members 45 and a jaw or anvil member pivotally connected to the other of said handle members and adapted to coöperate with said knife

carrying member, said jaw or anvil member having a bent slot formed therein and a pin 50 connected to said knife carrying member passing through said slot, whereby a slideable and pivotal connection between said members is provided.

3. In a device of the character described 55 and in combination, a pair of handle members pivotally connected together, one of which is adapted to serve as a base member, a knife carrying member having a slideable and pivotal connection with said base member, the other of said handle members also 60 having a pivotal connection with said knife carrying member, a jaw or anvil member pivotally connected to said second mentioned handle member and having a slideable and 65 pivotal connection with said knife carrying member.

4. In a device of the character described and in combination, a pair of handle members pivotally connected together, one of 70 which is adapted to serve as a base member, a knife carrying member having a slideable and pivotal connection with said base member, the other of said handle members also having a pivotal connection with said knife 75 carrying member, said knife carrying member being formed with spaced side members and a pin connection at the ends of said spaced side members to said base member to form said slideable and pivotal connection, a 80 jaw or anvil member extending between said spaced side members of said knife carrying member and pivotally connected to the other of said handle members, said jaw or anvil member having a slot formed therein, and a 85 pin secured to said spaced side members and passing through said slot, whereby said jaw or anvil member has a slideable and pivotal connection with said knife carrying member.

In testimony whereof we affix our signatures in the presence of two witnesses.

JOHN E. ARTHUR.
ROY L. ARTHUR.
